Attorney.

UNITED STATES PATENT OFFICE.

JOEL DICKINSON, OF NEWARK, NEW JERSEY.

DIE FOR FORGING PROJECTILES AND THE LIKE.

1,309,247.

Specification of Letters Patent.

Patented July 8, 1919.

Application filed January 18, 1919. Serial No. 270,896.

To all whom it may concern:

Be it known that I, JOEL DICKINSON, a citizen of the United States, and a resident of Newark, in the county of Essex and State 5 of New Jersey, have invented new and useful Improvements in Dies for Forging Projectiles and the like, of which the following is a specification.

The objects of this invention are to provide improved dies for pressing, hammering or forging both the cylindrical portion and the tapered end of a projectile at the same time; to provide such dies which can also be utilized for cutting off the large end of 15 the projectile after the same has been hammered or forged into shape; to secure the effect of a flat upper die in hammering the cylindrical portion of the projectile and yet enable the conical end to be shaped at the same time; to secure an improved product 20 without the loss of time or labor, and to obtain other advantages and results as may be brought out in the following description.

Referring to the accompanying drawings, 25 in which like numerals of reference indicate the same parts throughout the several views,

Figure 1 is a perspective view of the lower die of a pair embodying my invention;

Fig. 2 is a perspective view of the upper 30 die of a pair embodying my invention;

Fig. 3 is a side elevation of a pair of my improved dies slightly separated, and

Fig. 4 is an end view of the same.

In said drawing, 1 indicates the upper die 35 and 2 the lower die of a pair of forging dies of my improved construction, it being understood that the lower die 2 is adapted to be supported upon any suitable kind of a bed and the upper die held by its upper 40 part 3 in any suitable means, such as a hammer or press, by which it can be reciprocated up and down with respect to the lower die. I have not shown the bed or hammer, as these parts are old and well-known in the art and in no way affect the 45 relation of the dies to said parts as it has previously existed.

The face of the lower die has a longitudinal groove or recess 4 to receive the projectile, said groove or recess having a main substantially semi-cylindric portion which opens out through one end of the die 2, to receive the body of the projectile, the other end of the groove or recess being conically 55 tapered, as at 5, to shape the tapered end

of the projectile and opening at its point or apex through the other end of the die 2.

Through the side wall of this groove or recess 4 is a gap or notch 6 to receive a turning tool as is common and well-known 60 to those skilled in the art.

The face of the upper die 1 is stepped, as at 7, 8, the lower portion 8 being at that end of the die which forms the tapered end of the projectile and being recessed, as at 9, 65 to correspond to the lower die and fit said tapered end of the projectile. The other portion 7 of the upper die is substantially plane or flat and adapted to simply hammer the cylindrical portion of the projectile as 70 it lies in the groove or recess of the lower die.

It has been found that by the use of my improved forging dies as described, a projectile can be very effectively and accurately 75 shaped, both as to its cylindrical body portion and as to its conical or tapered end, and furthermore after such shaping, it is possible with my improved dies to cut off or square the large end of the projectile 80 ready for further operations upon the same. Heretofore it has been the practice to saw off this large end of the projectile, while still hot, and such an operation has been both expensive and dangerous, but with my 85 improved upper die the end of the projectile can be cut off by using a suitable cutter of the common knife type and employing the upper die as a hammer. Preferably the projectile, when ready for cutting, is re- 90 versed in its groove or recess, so as to bring the point of cutting central under the upper die, although still beneath its substantially plane or flat portion 8. Workmen then hold the cutter transversely of the projectile at 95 the point where it is to be cut off and strike it a blow with the upper die as a hammer; by turning the projectile and striking the cutter in its successive positions the projectile is quickly and squarely cut off at the 100 desired point, and furthermore it is done with little labor and loss of time and with no danger as it is a method of cutting off smaller rods and bars which is familiar to the workmen.

While I have shown my invention adapted for the forging of projectiles, it will be understood that it might be employed for other forgings having a body portion and a differently shaped end and which require to 110

be cut off at one end after forging; therefore I do not wish to be understood as restricting myself except as required by the following claims when construed in the light 5 of the prior art.

Having thus described the invention, what I claim is.

1. Forging dies of the character described, having in their coöperating faces one a 10 groove or recess with a body portion and a differently shaped end portion and the other a substantially plane portion opposite said body portion of the groove and a projecting end portion opposite the end portion of the 15 groove and correspondingly grooved or recessed, whereby the upper die may also be used as a hammer in cutting off the end of the forging.

2. Forging dies of the character described, 20 having in their coöperating faces one a groove or recess with a body portion opening through one end of the die and a differently shaped end portion and the other a substantially plane portion opposite said body portion of the groove and a projecting end portion opposite the end portion of the 25 groove and correspondingly grooved or recessed, whereby the upper die may also be used as a hammer in cutting off the end of the forging.

3. Forging dies of the character described, 30 having in their coöperating faces one a groove or recess with a body portion open-

ing through one end of the die and a differently shaped end portion and the other a substantially plane portion opposite said body portion of the groove extending from one end of the die past the middle of its face and a projecting end portion opposite the end portion of the groove and correspondingly grooved or recessed, whereby the upper die may also be used as a hammer in cutting off the end of the forging. 35

4. Forging dies of the character described, 40 having in their coöperating faces one a groove or recess with a semi-cylindric body portion and a differently shaped end portion and the other a substantially plane portion opposite said body portion of the groove and a projecting end portion opposite the end portion of the groove and correspondingly grooved or recessed, whereby the upper die 45 may also be used as a hammer in cutting off the end of the forging.

5. Forging dies of the character described, 50 having in their coöperating faces one a groove or recess with a semi-cylindric body portion and a tapered end portion and the other a substantially plane portion opposite said semi-cylindric body portion and a projecting end portion opposite the tapered portion and similarly grooved or recessed, whereby the upper die may also be used as a hammer in cutting off the end of the forging. 55

JOEL DICKINSON.
